UNITED STATES PATENT OFFICE.

AUGUST GERSTNER, OF RICHMOND HILL, NEW YORK.

NURSING BOTTLE AND ENVELOPE THEREFOR.

Application filed August 5, 1925. Serial No. 48,278.

This invention relates to an improvement in nursing bottles and envelopes therefor, and has for its object to provide a device of such shape that it will normally maintain a position upon an uneven surface, such as clothing and covers, without rolling or sliding about.

Another object is to provide a nursing bottle of substantially pyramidal shape whereby the contents of the bottle, when disposed horizontally as in use, will always be kept in contact with the nipple.

Another object is to provide an envelope, of soft pliable material, to receive the bottle, having an opening for the projection of the nipple therethrough, whereby the heated contents will be maintained at a uniform temperature for a considerable period.

Another object is to provide an envelope having laterally extending wings for positioning the bottle on an uneven surface.

Another object is to provide an envelope having a pocket arranged on its underside for the reception of a handkerchief or other similar article, whereby the substantially horizontal position of the bottle may be changed or regulated.

Another object is to provide certain improvements in the form, construction and arrangement of the several parts whereby the above named and other objects may be effectively attained.

The practical embodiment of my invention is represented in the accompanying drawings in which—

Fig. 1 represents a plan view of my improved envelope having the nursing bottle secured therein,

Fig. 2 represents a side elevation of the same,

Fig. 3 represents an end elevation of the same,

Fig. 4 represents a vertical section taken in the plane of the line 4—4 of Fig. 1 looking in the direction of the arrows,

Fig. 5 represents a plan view of the envelope in its open position and the bottle removed.

The envelope is formed of a relatively soft, pliable material, such as felt, natural or canton flannel, or other similar material and has a body portion of tubular and substantially pyramidal shape. The body comprises vertical side walls denoted by 1, 2, a top by 3 and a bottom by 4. The converging side walls, the top and the bottom of the

envelope form a relatively small opening 5 at one end, while the other end has a large opening 6. The opening 6 is closed by means of a laterally extending flap 7, the end 8 of which is arranged to be folded upwardly and over the top 3 of the envelope. The end 8 of this flap is provided with a fastening means, in the present instance, a button 9 and cord 10.

A side wing 11 extends laterally from the side wall 1 of the body, while a similar flap 12 extends outwardly from the side wall 2.

A nursing bottle 13 is of substantially pyramidal shape and has flat walls 14, a tubular neck 15 at the apex thereof, and a bottom 16.

A rubber nipple 17, of any well known and approved construction, is arranged to be removably secured to the neck 15. This bottle is inserted in the tubular body of the envelope so that the neck 15 and nipple 17 will project from the opening 5. The flap 7 contacts with the bottom 16 of the bottle, and the cord 10, one end of which is secured to the button 9, is passed toward and around the neck 15 of the bottle and thence back to the button, where it is wrapped around, and firmly secured as shown in Figs. 1, 2 and 4.

Thus it will be seen that the bottle is well covered and secured within the body of the envelope so that the contents of the bottle, if heated, will be maintained at a uniform temperature for a considerable period.

From the foregoing it will be understood that a device of this form and arrangement, when disposed horizontally as in normal use, will lie flat so that the contents within the bottle will always remain in the nipple until the bottle is empty. The laterally extending wings 11, 12, serve to prevent unintentional displacement of the bottle, as well as act as a means by which the bottle may be tilted or supported on an uneven surface, such as covers or clothing (not shown) upon which it may rest. The wings 11, 12 may also be used to removably secure the device to the covers or clothing by means of safety pins or other similar means (not shown).

The device may also be caused to assume various angles longitudinally, as well as transversely, by means of a pocket 18, which is secured to the bottom 4 of the body, and arranged to receive a handkerchief or other similar article (not shown). This pocket 18 is also of tubular form, similar to the body of the envelope, and has a relatively

- 2
- small opening 19 at one end and a larger opening 20 at the opposite end. The pocket may be formed of material similar to that of which the envelope itself is constructed, or it may be made of a textile or other similar fabric. When the surface upon which the device is to rest is uneven, a handkerchief may be inserted in the pocket 18, so that the bottom of the bottle 10 in the envelope is elevated and the liquid contents of the bottle caused to readily flow to the nipple.
- It will be understood that the envelope will protect the bottle from breakage if allowed to fall or contact with a hard surface.
- It will be understood that various changes may be resorted to in the form, construction and arrangement of the several parts without departing from the spirit and scope of my invention, and hence I do not intend to be limited to the details herein shown and described, except as they may be included in the claims.
- What I claim is:
- 25 1. An envelope for nursing bottles comprising, a tubular body of substantially rectangular in cross section and pyramidal shape for the reception of the bottle, said body having an outlet at its small end for the 30 nipple and an entrance at the large end for the insertion of the bottle, and a flap secured to one wall of the body adjacent said entrance and arranged to engage the bottom of the bottle for retaining the same in the 35 body.
2. An envelope for nursing bottles comprising, a tubular body of substantially rectangular in cross section and pyramidal shape for the reception of the bottle, said 40 body having an outlet at its small end for the nipple and an entrance at the large end for the insertion of the bottle, a flap secured to one wall of the body adjacent said entrance and arranged to engage the bottom of the 45 bottle for retaining the same in the body, and means on the opposite wall of the body for securing the free end of said flap to the body.
3. An envelope for nursing bottles comprising, a tubular body of substantially rectangular in cross section and pyramidal shape for the reception of the bottle, said 50 body having an outlet at its small end for the nipple and an entrance at the large end for the insertion of the bottle, a flap secured to one wall of the body adjacent said entrance and arranged to engage the bottom of the 55 bottle for retaining the same in the body, and wings disposed lengthwise and laterally of the body for positioning and preventing 60 unintentional displacement of the body.
4. An envelope for nursing bottles comprising, a tubular body of substantially rectangular in cross section and pyramidal shape for the reception of the bottle, said 65 body having an outlet at its small end for the nipple and an entrance at the large end for the insertion of the bottle, a flap secured to one wall of the body adjacent said entrance and arranged to engage the bottom of the 70 bottle for retaining the same in the body, means on the opposite wall of the body for securing the free end of said flap to the body, wings disposed lengthwise and laterally of the body for positioning and 75 preventing unintentional displacement of the body.
5. An envelope for nursing bottles comprising, a tubular body substantially rectangular in cross section for the reception 80 of the bottle, said body having an outlet for the nipple and an entrance for the insertion of the bottle, a flap secured to one wall of the body adjacent said entrance and arranged to engage the bottom of the bottle 85 for retaining the same in the body, and a handkerchief receiving pocket carried by the body for regulating the horizontal position of the body.
6. An envelope for nursing bottles comprising, a tubular body substantially rectangular in cross section for the reception 90 of the bottle, said body having an outlet for the nipple and an entrance for the insertion of the bottle, a flap secured to one wall of the body adjacent said entrance and arranged to engage the bottom of the bottle 95 for retaining the same in the body, and a handkerchief receiving pocket carried by the body for regulating the horizontal position of the body.
7. An envelope for nursing bottles comprising, a tubular body substantially rectangular in cross section for the reception 100 of the bottle, said body having an outlet for the nipple and an entrance for the insertion of the bottle, a flap secured to one wall of the body adjacent said entrance and arranged to engage the bottom of the bottle for retaining the same in the body, means on the opposite wall of the body for securing the free end of said flap to the body, and a handkerchief receiving pocket carried by the body for regulating the horizontal position of the body.
8. An envelope for nursing bottles comprising, a tubular body substantially rectangular in cross section for the reception 105 of the bottle, said body having an outlet for the nipple and an entrance for the insertion of the bottle, a flap secured to one wall of the body adjacent said entrance and arranged to engage the bottom of the bottle for retaining the same in the body, and a tubular handkerchief receiving pocket carried by the body for regulating the horizontal position of the body.
- 110 9. An envelope for nursing bottles comprising, a tubular body substantially rectangular in cross section for the reception of the bottle, said body having an outlet for the nipple and an entrance for the insertion of the bottle, a flap secured to one wall of the body adjacent said entrance and arranged to engage the bottom of the bottle for retaining the same in the body, and a tubular handkerchief receiving pocket 115 forming substantially to the shape of one wall and carried by the body for regulating the horizontal position of the body.
- 120 10. An envelope for nursing bottles comprising, a tubular body substantially rectangular in cross section for the reception of the bottle, said body having an outlet for the nipple and an entrance for the insertion of the bottle, a flap secured to one wall of the body adjacent said entrance and arranged to engage the bottom of the bottle for retaining the same in the body, and a tubular handkerchief receiving pocket 125 forming substantially to the shape of one wall and carried by the body for regulating the horizontal position of the body.
- 130 11. An envelope for nursing bottles comprising, a tubular body substantially rectangular in cross section for the reception of the bottle, said body having an outlet for the nipple and an entrance for the insertion of the bottle, a flap secured to one wall of the body adjacent said entrance and arranged to engage the bottom of the bottle for retaining the same in the body, and a tubular handkerchief receiving pocket 135 forming substantially to the shape of one wall and carried by the body for regulating the horizontal position of the body.

tangular in cross section for the reception of the bottle, said body having an outlet for the nipple and an entrance for the insertion of the bottle, a flap secured to one wall of the body adjacent said entrance and arranged to engage the bottom of the bottle for retaining the same in the body, a hand-kerchief receiving pocket carried by the body for regulating the horizontal position of the body, and wings disposed lengthwise and laterally of the body for positioning and preventing unintentional displacement of the body.

10 10. A nursing bottle provided with an

elongated rectangular base, two broad and 15 two narrow tapered sides uprising therefrom, said sides being inclined inwardly and terminating in a cylindrical neck.

11. A nursing bottle provided with an elongated rectangular base, two broad and 20 two narrow flat tapered sides uprising therefrom, said sides being inclined inwardly and terminating in a cylindrical neck.

In testimony, that I claim the foregoing as my invention, I have signed my name this 25 4th day of August 1925.

AUGUST GERSTNER.
